Primary Examiner — Kendra Leslie Hamilton*Assistant Examiner* — Jameson P Carey(74) *Attorney, Agent, or Firm* — Boudwin Intellectual Property Law, LLC; Daniel Boudwin(57) **CLAIM**

The ornamental design for a horse stall cleaning shovel, as shown and described.

DESCRIPTION

FIG. 1 is a top, front, left perspective view of a horse stall cleaning shovel showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top, front, left perspective view of the horse stall cleaning shovel shown in a condition of use, for clarity of disclosure.

The broken lines depict portions of the horse stall cleaning shovel that form no part of the claimed design.

1 Claim, 7 Drawing Sheets(56)
